UNITED STATES PATENT OFFICE.

ARTHUR WHITEHEAD AND GEORGE PORTEUS, OF LEEDS, ENGLAND.

MANUFACTURE OF STEREOTYPE-MATRICES.

No. 845,495.

Specification of Letters Patent.

Patented Feb. 26, 1907.

Application filed October 4, 1906. Serial No. 337,409.

To all whom it may concern:

Be it known that we, ARTHUR WHITEHEAD and GEORGE PORTEUS, subjects of the King of Great Britain, residing at Leeds, in the county of York, England, have invented certain new and useful Improvements in Manufacture of Stereotype-Matrices, and of which the following is a specification.

In producing stereotype-plates for printing purposes by the papier-mâché process the sheet of paper or other composition in which the matrix is to be formed, commonly termed the "flong," is laid on the type and then subjected to pressure either by rollers or otherwise, or according to another method is beaten into the type by a beating-brush, and the present invention refers to the latter mode of manufacture. In this latter process as now carried out the brush is manipulated by hand, and the flong should be evenly beaten and forced into the type until the proper depth is obtained, and to this end the blows of the beating-brush should be even and flat, since if the blows are delivered with one end or side of the brush there will be danger of breaking or tearing the flong and a matrix of uneven character will be produced, and it will be understood that such a mode of production by hand-beating is laborious, occupies considerable time, and the matrices so produced are extremely liable to be of uneven character.

Now the object of this invention is to provide a machine by which the brush is mechanically operated, while yet being very readily subject to control—that is, so constructed as to enable the operator to readily adjust the motions of the beating-brush so as to give the desired blows to suit the depth of the type or form from which the matrix is to be molded and to suit the character of the flong. To this end the machine according to this invention is constructed with a table to receive the type and flong, and above the table is a vertical sliding member having a beating-brush attached to its lower end, while its upper end is connected by a jointed rod to the crank of a crank-shaft which is continuously revolved by any suitable means.

To the joint in the rod, which joint lies between the crank and the sliding member, one end of a radius-arm is connected, and the opposite end of this arm is mounted on a pivot, which is normally held stationary, but can be adjusted so as to shorten or lengthen the distance between the points of connection of the

jointed rod—that is, between the point where the rod is pivoted to the crank and the point where it is pivoted to the sliding member. Mechanism is then provided by which the operator by means of a treadle can readily shift the pivot of the radius-arm, and so vary the throw of the sliding member, and consequently of the beating-brush which it carries, and means are also provided by which, having adjusted the pivot of the radius-arm, the operator can fix it in that position.

In the accompanying drawings is shown a constructional example of the invention, whereon:

Figure 1 is a front elevation, and Fig. 2 is a side elevation, of the matrix-molding machine; and Fig. 3 is a front elevation drawn to a larger scale to illustrate the locking arrangement for fixing the radius-arm in the position into which it has been placed.

Referring to the example illustrated, the machine consists of side standards 1, carrying a horizontal table 2, provided with a head-stock 3, formed with a projecting member 4, carrying a vertical sliding member 5, provided at its lower end with a box 6, carrying a beating-brush 7, while the upper end of the said sliding member 5 is provided with a cross-head 8, connected, through the medium of a jointed rod 9, to a crank 10, provided on a horizontal shaft 11, carried on bearings 12, situated at the upper end of the head-stock 3, which shaft 11 is provided with belt-pulleys 13, driven by some suitable motive power.

On a stud 14, carried by the head-stock 3, is pivoted a bell-crank lever 15, to one arm of which one end of a radius-arm 17 is pivoted at 18, while the other end of the arm 17 is connected to the joint 16 of the rod 9. The other arm of the bell-crank lever 15 is connected to a pivoted treadle-lever 19 through the medium of a connecting-rod 20, a double-armed lever 21, pivoted to the head-stock 3 at 22, and a connecting-rod 23, attached to a stud 24, provided on the said lever 15. On the rear end of the treadle-lever 19 is mounted a weight 25, which normally tends to hold the bell-crank lever 15 in such a position that the jointed rod 9 is rendered practically inoperative on the sliding member 5, carrying the brush 7.

In order to regulate the motion of the beating-brush in accordance with the depth of the type from which the matrix is to be molded, the movement given to the treadle-lever is capable of being limited and this limited

movement varied as required. To this end the front end of the treadle-lever 19 is connected with the frame of the machine by a two-part adjustable rod, (see Fig. 3,) comprising a vertical rod 26, pivoted on a stud 27, located on the treadle-lever 19, and a sleeve 28, pivoted on a stud 29, located on the under side of the table 2, which rod 26 is provided with a fixed spindle 30, carrying a plunger 31, working within the sleeve 28, while the latter is screw-threaded externally at 32 and formed with vertical slot-holes 33 for guiding the inner sliding stop 34, loosely mounted on the plunger-spindle 30 of the rod 26, which sliding stop 34 is adjustable in a vertical direction through the medium of a hand-wheel 35, mounted on the screwed portion 32 of the sleeve 28.

A means for locking the treadle 19 in the position into which it has been placed is provided in connection with the two-part adjustable rod, (see Fig. 3,) comprising a screw 36, attached to the rod 26, passing through a vertical slot 37, formed in the sleeve 28, which screw 36 is provided with a loose boss 38 and an external nut 39, whereby the rod 26 and its sleeve 28 may be connected together in any desired position at will.

The machine works as follows: The locking-nut 39 is first slackened so as to allow the weight 25 on the pivoted treadle-lever 19 to rock the latter and raise the rod 26 within its sleeve 28 and simultaneously raise the bell-crank lever 15 so as to bring the sliding brush-carrying member 5 into its uppermost position. The rotary motion then given to the crank 10 is taken up by the jointed rod 9, so that the sliding brush-carrying member 5 is rendered practically inoperative. The sliding stop 34 of the two-part rod is now adjusted so that the distance of the downward travel of the plunger 31 before coming onto the adjusted stop 34 is equal to that of the distance of the desired travel of the brush 7, and then upon depressing the treadle-lever 19 the bell-crank lever 15 is rocked and the jointed rod 9 straightened by the movement of the radius-arm 17. The brush-carrying member is then rapidly reciprocated in a vertical direction, and on a form of type with the flong in position thereon being placed on the table 2 under the reciprocating brush 7 a matrix of even character is speedily produced, while, if desired, the treadle-lever 19 may be locked in the down position when the machine is in action by fixing the rod 26 to its sleeve 28 through the medium of the screw 36, and then the manual pressure on the treadle-lever 19 can be removed.

In order to produce matrices of a large size, the head-stock and brush-operating mechanism can be duplicated, so as to give a larger brush-surface, in which case the table may be provided with a traveling carriage 65 for the reception of the forms.

What we claim as our invention, and desire to secure by Letters Patent, is—

1. A machine for effecting the brush method of molding papier-mâché matrices for producing stereotype-plates for printing; 70 consisting of a stationary table to support the type and flong, vertical stationary guides carried from the table, a vertical sliding member located in the guides, a brush at the lower end of the said member for acting upon the flong, bearings carried from the table, a revoluble shaft carried in the bearings, means for revolving the shaft, mechanism for connecting the shaft with the vertical sliding member for vertically reciprocating the latter, and means for regulating the distance of travel of the reciprocating brush-carrying member substantially as set forth.

2. A machine for effecting the brush method of molding papier-mâché matrices 85 for producing stereotype-plates for printing; consisting of a stationary table to support the type and flong, a head-stock above the table and vertical guides on the head-stock, a vertical sliding member located in the guides, a brush at the lower end of the said member for acting upon the flong, a crank-shaft carried by the head-stock, means for revolving the said shaft, a rod connecting the crank of the crank-shaft and the upper end of the brush-carrying sliding member, and a joint in the connecting-rod about centrally of its length, a radius-arm pivoted at one end to the joint of the connecting-rod, and means for controlling the position of the opposite end of the radius-arm to control and regulate the distance of travel of the reciprocating brush-carrying member by varying the relative angular positions of the two parts of the jointed connected rod, substantially as set forth.

3. A machine for effecting the brush method of molding papier-mâché matrices for producing stereotype-plates for printing; 110 consisting of a stationary table to support the type and the flong, a head-stock above the table and vertical guides on the head-stock, a vertical sliding member located in the guides, a brush at the lower end of the said member for acting upon the flong, a crank-shaft carried by the head-stock, and means for revolving the said shaft, a rod connecting the crank of the crank-shaft and the upper end of the brush-carrying sliding member, and a joint in the connecting-rod about centrally of its length, a bell-crank lever pivoted to the head-stock, a radius-arm pivoted at one end to the joint of the connecting-rod and at the other to one arm of the bell-crank lever, and means for regulating the position of the bell-crank lever to control and regulate the distance of travel of the reciprocating brush-carrying member substantially as set forth.

4. In a machine for effecting the brush method of molding papier-mâché matrices for producing stereotype-plates for printing;

the combination with a stationary table to support the type and flong, a head-stock upon the table, vertical guides in the front face of the head-stock, a vertical sliding member located in the guides, a brush at the lower end of said member for acting upon the flong, a shaft carried by the head-stock, a crank at the forward end of the said shaft, a crank-pin on the crank, means for revolving the said shaft, a rod connecting the crank-pin and the upper end of the brush-carrying sliding member, a joint in the connecting-rod about centrally of its length, a bell-crank lever pivoted to the head-stock, a radius-arm connecting the joint of the connecting-rod to the first arm of the bell-crank lever, a treadle-lever pivoted below the table, a two-armed lever pivoted above the table, a connecting-rod from one end of the treadle-lever to one arm of the two-armed lever above the table, and a connecting-rod from the other arm of the latter lever to the second arm of the bell-crank lever, and a counterweight on the treadle-lever tending to maintain the bell-crank lever and radius-arm in a position to render the sliding member practically inoperative substantially as set forth.

5. In a machine for effecting the brush method of molding papier-mâché matrices for producing stereotype-plates for printing; the combination with a stationary table to support the type and flong, a head-stock upon the table, vertical guides in the front face of the head-stock, a vertical sliding member located in the guides, a brush at the lower end of the said member for acting upon the flong, a shaft carried by the head-stock, a

crank at the forward end of the said shaft, a crank-pin on the crank, means for revolving the said shaft, a rod connecting the crank-pin and the upper end of the brush-carrying sliding member, a joint in the connecting-rod about centrally of its length, a bell-crank lever pivoted to the head-stock, a radius-arm connecting the joint of the connecting-rod to the first arm of the bell-crank lever, a treadle-lever pivoted below the table, a two-armed lever pivoted above the table, a connecting-rod from one end of the treadle-lever to one arm of the two-armed lever above the table, and a connecting-rod from the other arm of the latter lever to the second arm of the bell-crank lever, a counterweight on the treadle-lever tending to maintain the bell-crank lever and radius-arm in a position to render the sliding member practically inoperative, a two-part telescopic rod pivoted at one end to the treadle-lever and at the other end to the table, means for clamping the two parts of the rod together to hold the treadle-lever stationary when required, and means for limiting and regulating the distance of movement allowed between the two parts of the telescopic rod and thereby limiting the movement of the treadle-lever substantially as set forth.

In witness whereof we have hereunto set our hands in presence of two witnesses.
